UNITED STATES PATENT OFFICE.

FRANCIS S. MADDAFORD, OF BALTIMORE, MARYLAND, ASSIGNOR TO CROSSE AND BLACKWELL, INC., OF BALTIMORE, MARYLAND, A CORPORATION OF MARYLAND.

DESIGN FOR A BOTTLE.

Application filed September 28, 1928. Serial No. 28,319. Term of patent 7 years.

To all whom it may concern:

Be it known that I, FRANCIS S. MADDAFORD, a citizen of Great Britain, residing at Baltimore, in the county of Baltimore and State of Maryland, have invented a new, original, and ornamental Design for Bottles, of which the following is a specification, reference being had to the accompanying drawings, forming a part thereof.

Fig. 1 is a side elevation.

Fig. 2 is a side elevation, the bottle being turned 90° from the Fig. 1 position.

Fig. 3 is a side elevation of the bottle turned 180° from the Fig. 1 position.

Fig. 4 is a fragmentary horizontal sectional view thru the body of the bottle, showing the cross-sectional shape of the flutes and facets.

I claim:

The ornamental design for a bottle, substantially as shown.

Signed at Baltimore, in the county of Baltimore and State of Maryland, this 25th day of September, 1928.

FRANCIS S. MADDAFORD.
